UNITED STATES PATENT OFFICE.

MARTIN GEBHARDT, OF NEW YORK, N. Y.

DESIGN FOR A RING OR SIMILAR ARTICLE.

SPECIFICATION forming part of Design No. 32,079, dated January 9, 1900.

Application filed December 6, 1899. Serial No. 739,451. Term of patent 7 years.

To all whom it may concern:

Be it known that I, MARTIN GEBHARDT, of the city of New York, borough of Brooklyn, and State of New York, have invented and produced a certain new and original Design for Rings or Similar Articles, of which the following is a full, clear, and exact description, reference being had to the accompanying drawings, wherein—

Figure 1 is a plan view of my newly-invented design; Fig. 2, a side elevation of a ring, showing the design.

The center of the design is composed of three oval panels a , a' , and a^2 . Middle panel a is larger than panels a' and a^2 , adjoining it one from each side. The centers of all three panels are in line with each other and in line with the center line of the band b . On the same center line are set, symmetrically to each side of the panels, rosettes c and c' , representing a beautified form of Maltese crosses, with a center field marked by a circle proportionate in size to the size of the rosettes.

Rosettes c are larger than rosettes c' . They are set immediately adjoining the panels a' and a^2 . Rosettes c' are set approximately in center of the field inclosed by scrolls d , forming the termini of the ornament.

Connecting with scrolls d and panels a' and a^2 , respectively, are scrolls e and volutes f , forming, respectively, the upper and lower outlines on the left side of the design and reversely on the right side thereof.

Ionic scrolls g and h complete the outlines of the design between the scrolls e and volutes f . 35

The configuration of scrolls g corresponds to that of the under part of volutes f , placed opposite them, adjoining the edges of panels a' and a^2 , respectively. Scrolls h are placed 40 in corresponding position adjoining the edge of panel a . This arrangement of the scrolls gives the design the appearance as if the curves surrounding panels a , a' , and a^2 be shifted somewhat to the right side of the figure, 45 this effect being also supported by the position of the scrolls d . In fact, however, the ornament is symmetrical, though the two halves thereof are reversed from top to bottom.

Panels a , a' , and a^2 are slightly raised above 50 the plane of the field i , but not higher than the curves of the design. Rosettes c and c' , set upon the matted fields i , as hereinbefore described, are in lower plane.

The edges of the ornamental curves composing the design are slightly scalloped in the parts as indicated in the drawings, whereas the opposite surfaces are highly polished. 55

I claim—

The design for a ring or similar article as 60 herein shown and described.

MARTIN GEBHARDT.
